tion of Delaware

Filed Apr. 14, 1958, Ser. No. 728,210

7 Claims. (Cl. 260—397.5)

This invention relates to 17-alkoxy-1,3,5(10)-estratrien-3,16-diols, to esters thereof and to methods of preparing the same. More particularly, this invention relates to novel steroids having the following general formula

wherein R is a lower alkyl radical containing 1 to 5 carbon atoms and X is hydrogen or an acyl radical containing 1 to 18 carbon atoms.

In the foregoing compounds the radical R represents alkyl radicals such as methyl, ethyl, propyl, isopropyl, butyl, sec-butyl, isobutyl, amyl, sec-amyl, and isoamyl. The acyl radicals represented by X include alkanoyl radicals such as acetyl, propionyl, butyryl, palmityl, stearyl and the like, as well as benzoyl, toluyl, naphthoyl and similar aromatic acyl radicals.

The compounds of this invention are estrogen derivatives which have the valuable property of stimulating the reticuloendothelial system without exhibiting estrogenic activity. For instance, estriol exhibits estrogenic activity in rats at a dosage of 10 micrograms subcutaneously or orally, but the compounds of this invention show only the slight estrogenic activity at much higher dosages.

The reticuloendothelial system plays an important role in cholesterol metabolism. Cholesterol-containing macromolecular aggregates appear to be phagocytosed by cells of the reticuloendothelial system. Stimulation of the reticuloendothelial system will accelerate the reduction of blood cholesterol levels. It has been observed that premenopausal women are virtually immune from coronary thrombosis and these observations led to the study of the effect of certain estrogens in experimental and clinical atherosclerosis. These studies indicate that certain estrogens cause a clinical improvement, as well as a reversion toward normal of the blood lipid picture in hypercholesterolemic individuals. On the basis of such studies it has been concluded that the estrogens may have a useful role in therapy or prophylaxis of disorders associated with abnormal concentrations of cholesterol in the blood and that the efficacy of these substances may be due to their stimulating effect upon the reticuloendothelial system. A major limiting factor in the clinical use of estrogens lies in their concomitant sexual effect. Therefore, it is desirable to produce steroids having a stimulating effect on the reticuloendothelial system without the undesired sexual activity.

It is an object of this invention to provide steroids which stimulate the reticuloendothelial system which have negligible estrogenic or other sexual effect. It is another object of this invention to provide efficient methods for

2

producing such steroids. An additional object is to provide novel steroids having desirable physiological properties. A further object is to provide new and useful 17-alkoxy-1,3,5(10)-estratrien-3,16-diol compounds. 5 These and other objects will be apparent from and are achieved in accordance with the following disclosure taken in conjunction with the attached drawing which forms a part hereof.

In the single sheet of drawing there is illustrated a 10 process diagram of the production of 17 beta-methoxy-1,3,5(10)-estratrien-3,16 beta-diol (III) and 17 beta-methoxy-1,3,5(10)-estratrien-3,16 alpha-diol (V) starting with 16-keto estradiol (I). The latter is methylated with dimethyl sulfate or similar methylating agent in the 15 presence of aqueous alkali and a mixture of 16-keto estradiol-17-methyl ether (II) and the corresponding 3,17-dimethyl ether is formed. The monomethyl ether (II) can be separated from the dimethyl ether by proper adjustment of the pH of the solution. (II) can then be 20 reduced with an alkali metal borohydride or similar reagent to the corresponding 16 beta-ol compound (III). By reduction of (II) with sodium and a lower alcohol (containing 1 to 5 carbon atoms) the corresponding 16 alpha-ol epimer (V) can be produced. In order to purify 25 (III) it is convenient to react it with an acetylation agent to produce the diacetate (IV) which can be purified readily and then hydrolyzed to 17 beta-methoxy-1,3,5(10)-estratrien-3,16 beta-diol (III).

The 17-alkoxy-1,3,5(10)-estratrien-3,16-diols represented by the structural formula given above are useful 30 medicinal agents by virtue of their property of stimulating the reticuloendothelial system of animals and humans, thereby aiding in the therapy or prophylaxis of disorders associated with abnormal concentrations of cholesterol in the blood stream, such as atherosclerosis, arteriosclerosis, coronary thrombosis and the like. The compounds of this invention can be administered by parenteral or oral routes, such as by subcutaneous or intramuscular injection in suitable vehicles, or in preparations for oral ingestion. At the dosages necessary for 35 stimulation of the reticuloendothelial system, these compounds do not exhibit estrogenic or other sex hormone activity and, therefore, appear to be without undesired side effects or toxicity. For instance, 17 beta-methoxy- 40 1,3,5(10)-estratrien-3,16 beta-diol (III) when injected in adrenalectomized mice at a dosage of approximately 1 milligram per kilogram produces a 26% increase in the white blood cell count, evidencing stimulation of the reticuloendothelial system, within 3 hours. At that dosage 45 level no more than a slight estrogenic effect is observed.

The invention is disclosed in further detail by the 50 means of the following examples which are provided for purposes of illustration only and which are not to be construed as limiting the scope of the invention. It will be appreciated by those skilled in the art that numerous modifications in synthetic procedures may be adopted without departing from this invention, such as the use of equivalent solvents, reagents, conditions and the like.

60

EXAMPLE 1

17 beta-methoxy-1,3,5(10)-estratrien-3-ol-16-one

To a solution of 4 grams of 16-ketoestradiol (I) and 2400 ml. of 0.5 N lithium hydroxide solution was added 65 32 ml. of dimethyl sulfate and the mixture was shaken for 30 minutes at room temperature. Then 28 ml. of additional dimethyl sulfate were added and the shaking continued for 30 minutes longer. Then the mixture was allowed to stand for about 15 hours at room temperature after which it was filtered to remove a precipitate of 70 16-ketoestradiol dimethyl ether. The filtrate was treated with solid carbon dioxide until the pH was re-

duced to 7.0-7.5 and then extracted with 2 liters of ether. The ether solution was washed with a liter of 3% sodium bicarbonate solution and with a liter of water. The ethereal solution was then evaporated to dryness on a steam bath and the residue of precipitate weighing 720 mg. was dried at 35° C. This product was 16-ketoestradiol-17-methyl ether (II). It was dissolved in 100 ml. of methanol, treated with activated charcoal, filtered and the filtrate evaporated until crystallization occurred. The crystals of 16-ketoestradiol-17-methyl ether (II) were collected on a filter, washed with 66% methanol at room temperature. On further recrystallization from 80% aqueous methanol, there were obtained crystals of 16-ketoestradiol-17-methyl ether melting at 271-272° C. (with decomposition).

EXAMPLE 2

17 beta-methoxy-1,3,5(10)-estratrien-3,16 beta-diol

To a solution of 1.01 grams of 16-ketoestradiol-17-methyl ether (II) in 800 ml. of 0.2 N potassium hydroxide solution was added 500 mg. of potassium borohydride, the temperature of the solution being maintained at 0 to 2° C. The reaction mixture was allowed to stand at ice temperature for a few hours and then allowed to warm up to room temperature over night. 20 ml. of acetone were added to destroy the excess of potassium borohydride and then the pH of the solution was reduced to 3 with concentrated hydrochloric acid and the resulting solution was refrigerated for about 24 hours. The precipitate of 17 beta-methoxy-1,3,5(10)-estratrien-3,16 beta-diol (III) was removed, washed well with water and dried at 35° C. It was recrystallized from 55% methanol and there was obtained 450 mg. of impure product melting not sharply at around 245° C. This material was purified by the procedure of Example 3.

EXAMPLE 3

The 450 mg. of crude 17-methoxy-1,3,5(10)-estratrien-3,16 beta-diol (III) from Example 2 was dissolved in 50 ml. of pyridine and treated with 50 ml. of acetic anhydride. The resulting solution was swirled at room temperature and allowed to stand over night. The next day a liter of ice water was added to the solution and the mixture was refrigerated. A precipitate of 17-methoxy-1,3,5(10)-estratrien-3,16 beta-diol diacetate (IV) was collected on a filter, washed well with water and dried. The yield was 590 mg. of compound melting at 119-120° C. On further recrystallization the melting point of this product can be increased to 120.5-121° C.

By analogous procedures using equivalent quantities of butyryl chloride, benzoyl chloride, palmitic anhydride, stearyl chloride or beta-naphthoyl chloride in lieu of acetic anhydride, there are produced 17-methoxy-1,3,5(10)-estratrien-3,16 beta-diol dibutyrate, dibenzoate, dipalmitate, distearate or dinaphthoate.

The 17 beta-methoxy-1,3,5(10)-estratrien-3,16 beta-diol diacetate (IV) prepared above was dissolved in 320 ml. of hot methanol to which was added 160 ml. of 2.0 N sodium hydroxide solution. The resulting solu-

tion was refluxed for 1 hour, then diluted with 60 ml. of water and evaporated down until ebullation almost ceased. The solution was then cooled to room temperature and adjusted to pH 3 with hydrochloric acid. On cooling a precipitate of 17 beta-methoxy-1,3,5(10)-estratrien-3,16 beta-diol (III) was formed which was removed, washed with water, dried and recrystallized from 80% methanol. The recrystallized product melted at 244-245° C. and amounted to 270 mg.

EXAMPLE 4

17 beta-methoxy-1,3,5(10)-estratrien-3,16 alpha-diol

To a solution of 500 mg. of 16-ketoestradiol-17-methyl ether (II) in 100 ml. of n-propyl alcohol heated to reflux was added 3.3 grams of sodium in small pieces over a period of 75 minutes. The reaction mixture was diluted with 1 liter of ice water and refrigerated over night. The precipitate of 17 beta-methoxy-1,3,5(10)-estratrien-3,16 alpha-diol (V) was collected on a filter, washed well with water and dried.

What is claimed as new and is desired to be secured by Letters Patent of the United States is:

1. A compound of the formula

wherein R is a lower alkyl radical containing 1 to 5 carbon atoms and X is a member of the group consisting of hydrogen and hydrocarbon acyl radicals containing 1 to 18 carbon atoms.

2. 17 beta-alkoxy-1,3,5(10)-estratrien-3,16-diol wherein the alkoxy group contains 1 to 5 carbon atoms.

3. 17 beta-methoxy-1,3,5(10)-estratrien-3,16 beta-diol.

4. 17 beta-methoxy-1,3,5(10)-estratrien-3,16 alpha-diol.

5. 17 beta-methoxy-1,3,5(10)-estratrien-3,16-diol diacetate.

6. A method of producing 17 beta-methoxy-1,3,5(10)-estratrien-3,16 alpha-diol which comprises reacting 16-keto-estradiol-17-methyl ether with a reducing agent comprising an alkali metal and a lower alkanol to reduce the 16-keto radical to a 16 alpha-hydroxyl radical.

7. The method of claim 6 wherein the reducing agent is sodium and propanol.
